DESIGN FOR A FLOOR MAT

Don R. Cotterman, Pontiac, Mich., assignor to Baldwin Rubber Company, Pontiac, Mich., a corporation of Michigan

Application May 2, 1938, Serial No. 76,936

Term of patent 7 years

To all whom it may concern:

Be it known that I, Don R. Cotterman, a citizen of the United States of America, residing at Pontiac, in the county of Oakland and State of Michigan, have invented a certain new, original, and ornamental Design for a Floor Mat, of which the following is a specification, reference being had therein to the accompanying drawing, forming a part thereof, wherein: Figure 1 is a plan view of a floor mat embodying my new design; Figure 2 is a cross sectional view taken substantially on the plane indicated by the line 2—2 of Figure 1; and, Figure 3 is a cross sectional view on line 3—3 of Figure 1.

The broken lines on the exterior edge are for illustrative purposes to indicate indeterminate size.

I claim:

The ornamental design for a floor mat, substantially as shown and described.

DON R. COTTERMAN.
